UNITED STATES PATENT OFFICE

EDWIN HAROLD BRAATELIEN, OF PHOENIX, ARIZONA

SPRAY DEVICE

Application filed September 10, 1929. Serial No. 391,596.

This invention appertains to new and useful improvements in spraying devices and more particularly to a novel spray for dampening and maintaining fresh fruit, vegetables, and the like.

The principal object of this invention is to provide a spraying device which will produce a very fine vaporous form of water spray.

10 During the course of the following specification and claim, numerous other important objects and advantages of the invention will readily become apparent.

In the drawings:

15 Figure 1 represents a side elevation of the novel device.

Figure 2 represents an edge elevation of the novel spray.

Figure 3 represents a horizontal sectional view through the device looking downwardly.

Referring to the drawings, wherein like numerals designate like parts, it will be seen that 5 denotes the water supply pipe which is threaded at its upper end as at 6.

20 25 The invention includes an internally threaded cap 7 for engagement over the threaded end portion of the pipe 5 and this cap 7 has a small threaded opening therein for receiving the threaded reduced portion of the nipple 8. This nipple 8 has a very fine bore 9 extending longitudinally therethrough and communicating with the pipe 5.

Arranged above the cap 7 is a frame consisting of the side members 10-10 and the cross member 11 connecting the upper ends thereof. Depending from the intermediary of the cross member 11 is an elongated pin 12, which serves as a deflector for the stream of water discharged from the bore 9. The 30 35 40 lower end of the pin 12 is tapered as at 13, and this pin is constructed of some suitable plastic material so that it may be readily bent to a perfect alined position with respect to the bore 9 so that the spray produced will be 45 uniform.

Obviously, in the manufacture of this novel device, numerous changes in the shape, size and materials may be resorted to without departing from the spirit and scope of the invention as claimed hereinafter,

Having thus described the invention, what is claimed as new is:

A spraying device comprising a cap having means for attachment to the discharge end of a water supply pipe, a discharge nipple on the said cap, a frame projecting from the cap and consisting of side members and a cross member connecting the outer end of the side members, and a deflector consisting of an elongated pin of plastic material projecting inwardly from the cross member of the frame and having its lower end tapered, said pin being capable of being bent for alinement with the discharge opening of the said nipple to produce a uniform spray.

In testimony whereof I affix my signature.

EDWIN HAROLD BRAATELIEN.
